(57) **CLAIM**

The ornamental design for a portable color matching tool for shopping consumers, as shown and described.

DESCRIPTION

FIG. 1 is a perspective view of a portable color matching tool for shopping consumers according to the new design.

FIG. 2 is an elevation view from the front.

FIG. 3 is an elevation view from the rear.

FIG. 4 is a top plan view.

FIG. 5 is a bottom plan view.

FIG. 6 is an elevation view from the left side in FIG. 2; and,

FIG. 7 is an elevation view from the right side in FIG. 2.

The broken line showing is included for the purpose of illustrating non-claimed subject matter and forms no part of the claimed design.

For ease of illustration, the broken line showing is not the present in FIGS. 3–7.
